JOINT FOR ARTIFICIAL LIMB

Johann W. Bach, Germaniaplatz 267,
Essen-Borbeck, Germany

Filed July 3, 1961, Ser. No. 121,564

Claims priority, application Germany Nov. 30, 1960
6 Claims. (Cl. 3—27)

My present invention relates to prosthetic limbs and more particularly to a physical joint, such as a knee joint, for such limbs.

It is an object of my invention present to provide a prosthetic limb with a physiological joint which kinematically and cosmetically, i.e., both in the relatively mobility of the parts and in its outer appearance, closely approximates the corresponding joint of a natural limb.

It is another object of the present invention to provide an artificial limb which is long-wearing and requires practically no adjustment even after protracted use.

A further object of this invention is the provision of improved means in an artificial limb adapted to prevent buckling at a joint substantially in the manner of a natural knee cap.

Another object of the present invention is to provide a jointed artificial limb of simple design, low weight and aesthetic appearance adapted to be used as an exposed appliance on, for example, a bathing beach.

In accordance with this invention I provide a joint for hingedly interconnecting two members of a prosthetic appliance, such as a thigh portion and a shank portion, which resembles an anatomical knee joint and includes a knuckle-shaped termination on one (usually the upper) member co-operating with a complementary socket-shaped termination on the other member. The two terminations have substantially cylindrical rolling surfaces of different radii for relative swinging and sliding movement, the knuckle being provided with a hinge pin or shaft which extends in the direction of its cylinder axis (e.g., is in line with it) and is so disposed that in standing position this shaft lies rearwardly of the center of gravity of the load supported by the appliance whereby the body weight of the wearer tends to cause a forward swing of the artificial thigh from its substantial alignment with the artificial shank. One or more flexible straps, e.g., of steel or nylon, are anchored to the socket and looped around the shaft in corresponding recesses of the knuckle so as to facilitate relative bending of the members; to prevent the aforementioned forward swing beyond the erect position, suitable anti-buckling means may be provided, advantageously in the shape of one or more abutments on the knuckle bearing upon the retaining strap or straps from the front to limit the extent of relative rotation of the members. The retaining straps, which in a preferred embodiment have the shape of V-belts, may be provided with means accessible through a suitable window in the socket-forming member for adjusting their tension, e.g., for the purpose of compensating for creeping elongation thereof.

The main advantages of prosthetic limbs with physiological knee joints according to my invention are their relatively constant kinematical properties, their very good cosmetic qualities, a relative simple design, and their possibility of being made entirely from non-metallic parts with consequent decrease in weight.

These and other objects, features and advantages of my present invention will become more clearly apparent from the following description of a preferred embodiment of the invention, given in conjunction with the accompanying drawing in which:

FIG. 1 is a section side view of a prosthetic limb according to the present invention;

2

FIG. 2 is a front view of the limb shown in FIG. 1;

FIG. 3 is a rear view of the same;

FIG. 4 is a sectional view of the limb taken along line IV—IV of FIG. 1; and

5 FIG. 5 is a side view of the prosthetic limb in a bent position.

The artificial limb shown in the drawing comprises a thigh member 2 and a hollow shank member 1 connected by a knee joint 12. The lower part of the thigh portion 10 2 ends in a knuckle 4 having a substantially cylindrical rolling surface with a portion 5 of transitional curvature. The knuckle 4 is divided by two recesses 13a, 13b into three protruding sections 4a, 4b, 4c whose outer areas 15 form a cylindrical rolling surface. These sections are supported by respective antifriction strips 14a, 14b, 14c, preferably made of plastic (e.g., a polyacrylate or polytetrafluoromethane), on the upper part of the shank 1 which ends in a socket 3 co-operating with the knuckle 4 to form the joint 12. The socket 3 is provided with two 20 projecting portions 3a, 3b which enter the recesses 13a, 13b between the cylindrical socket portions 4a, 4b, 4c; these portions have a radius somewhat smaller than that of the concave upper surface of socket 3 on which they are cradled and to which the antifriction strips 14a, 14b, 25 14c are fastened by screws 17.

A shaft 7 passes through the knuckle portions 4a, 4b, 4c approximately along the geometrical axis of their cylindrical rolling surface. Two parallel V-belt straps 8a, 8b are anchored to the socket 3 within the cavity of the 30 hollow shank 1 and are respectively accommodated by the recesses 13a, 13b within which they are looped around the shaft 7. The straps 8a, 8b pass through socket 3 via two openings 18' near the shin side and two openings 18" near the calf side of the shank 1 and are anchored at 35 their front ends by cotter pins 11' bearing upon the upper wall 6 of the shank cavity. The rear extremities of the straps 8 are adjustably fastened by cotter pins 11' which bear upon one or more gaskets 15. An elastic block 10 is interposed between the gaskets 15 and the wall 6. The 40 tension in the straps 8 may be increased by adding further gaskets 15 through a window 16 which is conveniently provided in the upper calf section of the shank 1 to give access to its interior. Stops 9 in the front sections of the recesses 13a, 13b abut the V-belts 8a, 8b in the 45 straightened portion of the jointed limb to limit the forward swing of thigh 2 about shaft 7.

The operation of the prosthetic limb joint according to my present invention may be best described with reference to FIGS. 1 and 5. In the bent state illustrated in 50 FIG. 5 the thigh member 2 and the shank member 1, held together at the joint 12 by the straps 8a, 8b, occupy a relative position in which shaft 7 lies somewhat forwardly of the vertical radial plane of the rolling surface of socket 3, owing to the weight distribution of the lower 55 member 1 which is suspended from the joint 12 by the straps 8a, 8b in the seated position of the amputee. As the leg is straightened, the center of rotation of the knuckle 4 as represented by the shaft 7 slides slightly toward the rear as the body weight of the wearer shifts 60 the erect thigh 1 from the dot-and-dash position of FIG. 1 to the solid-line position thereof. Now the stops 9 bear upon the straps 8a, 8b and through them upon the ridges 3a, 3b of the socket 3, thereby limiting the forward 65 swing of the thigh 2 which together with the body weight 70 supported by it has a center of gravity located in this position forwardly of the shaft 7, i.e., to the left of it as viewed in FIG. 1. The joint is therefore locked against buckling in this position and remains so until the weight of the wearer is transferred to the other leg. The kinematics of the artificial joint 12 therefore follow closely those of a natural knee joint.

Various modifications may suggest themselves to those

skilled in the art and may be adopted without departing from the spirit and scope of my invention and, hence, I do not wish to be restricted to the details shown and described, except to the extent indicated in the appended claims.

I claim:

1. A prosthetic limb comprising a thigh member and a shank member interconnected by a knee joint, said thigh member being provided with a substantially cylindrical knuckle portion forming part of said joint, said shank member having a substantially cylindrically concave bearing surface receiving said knuckle portion for rolling displacement thereon, a shaft on said knuckle portion extending in the direction of the cylinder axis thereof, and flexible link means yieldably embracing said shaft and projecting from said bearing surface, said shaft being positioned rearwardly of the center of gravity of the thigh-supported load in an erect position of the wearer, said bearing surface having a cylinder radius slightly greater than that of said knuckle portion for enabling the latter to roll forwardly in said erect position, further comprising anti-buckling means on one of said members for limiting the forward rolling of said knuckle portion.

10

15

20

2. A prosthetic limb according to claim 1 wherein said anti-buckling means comprises an abutment on said knuckle portion engageable with said link means in said limiting position.

3. A prosthetic limb according to claim 1 wherein said knuckle portion is provided with a plurality of recesses axially dividing it into sections, said link means comprising a plurality of straps respectively looped in said recesses about said shaft.

4. A prosthetic limb according to claim 3 wherein said surface is provided with a plurality of upstanding ridges respectively entering said recesses for centering said knuckle portion thereon.

5. A prosthetic limb according to claim 3 wherein said straps are V-belts.

6. A prosthetic limb according to claim 3 wherein said bearing surface is provided with a plurality of anti-friction strips respectively supporting said sections.
